[57] CLAIM

The ornamental design for a travel toothbrush with floss, as shown and described.

DESCRIPTION

FIG. 1 is a perspective view of my travel toothbrush with floss;

FIG. 2 is a right side view, in which the left side, except for the absence of the dental floss opening, is a mirror image thereof;

FIG. 3 is a top plan view thereof;

FIG. 4 is a bottom plan view of my design for a travel toothbrush;

FIG. 5 is an upper end view thereof;

FIG. 6 is a lower end view of my inventive design for a travel toothbrush; and,

FIG. 7 is a perspective view showing the end cap, covering an internal roll of dental floss, partially removed from the handle portion thereof.
